UNITED STATES PATENT OFFICE

WILLIAM A. EDWARDS, OF CHICAGO, ILLINOIS, ASSIGNOR TO STEWART-WARNER CORPORATION, OF CHICAGO, ILLINOIS, A CORPORATION OF VIRGINIA

FUEL FEEDING DEVICE

Application filed October 23, 1929. Serial No. 401,871.

The purpose of this invention is to provide an improved fuel feeding device for supplying an internal combustion engine, particularly adapted for utilizing the vapor of the fuel, which under certain conditions is formed in the apparatus, for offsetting the variation of the fuel mixture which sometimes results from air drawn into the intake manifold from the vacuum chamber while the suction valve is open. The invention consists in the elements and features of construction shown and described as indicated in the claims.

In the drawings:

Figure 1 is a diagrammatic view showing a vacuum tank embodying this invention in its position on the vehicle relative to the intake manifold and carbureter.

Figure 2 is a vertical axial section of the fuel feeding device embodying the invention.

Figure 3 is a detail section showing in side elevation the float stem connection with the atmosphere valve stem.

Referring to the drawings:

The engine intake manifold is indicated at X, the carbureter at Y, and the vacuum tank in its entirety at Z.

In detail the vacuum tank comprises the outer or reserve fuel chamber, A, and the inner or vacuum chamber, B, the latter being telescopingly mounted within the upper part of the reserve chamber, A, the detail construction for that purpose being that the reserve chamber, A, is closed at the top by a cap member, A¹, which is a metal stamping formed with a flange, a¹, fitting outside the upper end of said chamber, A, said stamping being made to form a cylindrical shoulder, a², and said cap having a central aperture, indicated at a³, for admitting the vacuum chamber, B, which is dimensioned for fitting said aperture, and has an out-turned flange, b¹, lapping the margin of the aperture, a³. The chamber, B, is provided

with a cap, B¹, having a down-turned marginal flange, B¹⁰, fitting outside the cylindrical shoulder, a², of the cap member, A¹, of the outer chamber. A packing gasket, b⁴, is interposed between the flange, b¹, and the web of the cap, B¹, for rendering the vacuum

chamber fluid-tight. A gasket, b⁵, is also shown interposed between said flange, b¹, and the inner marginal flange, a⁴, of the cap, A¹, but inasmuch as the outer chamber, A, necessarily has an atmosphere vent, shown at 55 33, this precaution is not essential. The several parts mentioned are secured together by clamp screws, a⁶, taking through the several lapped flanges and the intervening gaskets. 60

For like reason, viz., that the chamber has atmosphere vent, the cap, A¹, need not be fitted airtight over the upper end of the chamber, A but is made a fairly snug fit to prevent too easy or accidental displacement. 65

The construction as thus far described it will be understood facilitates assembling and disassembling of the parts, since the inner vacuum chamber, B, may be withdrawn without detaching the cap, and therefore 70 without necessity for releasing any of the clamp screws, a⁶, since the cap, A¹, may be withdrawn from the chamber, A, with the chamber, B.

In the horizontal web of the cap, B¹, there 75 is mounted a fuel inlet fitting, F, for connection with the fuel supply pipe, f, indicated in Figure 1 as leading to the main fuel tank at the rear of the vehicle. The inner end of the fitting, F, is furnished with a 80 strainer, F¹, as seen in Figure 2.

At the center of the horizontal web of the cap, B¹, of the vacuum chamber, there is mounted a fitting, E, arranged for connection with the pipe, e, leading from a suction 85 source indicated in Figure 1 as the intake manifold of the engine. The fitting, E, has a restricted passage, 20, constituting the suction inlet. For convenience of guiding the float stem, as hereinafter explained, there is 90 secured rigidly to the inner end of the fitting, E, at the inner end of the passage, 20, a short tube, 25. This tube has no function in connection with the suction, advantage being merely taken of the presence of the 95 duct, 20, for securing this guide tube to the fitting, E, a tube being employed instead of a rod, as necessary to avoid closing the inlet passage.

The fitting, E, is bored from its inner end, 100

as seen at 26, to form the atmosphere valve chamber, and for a connection, as herein-after described, leading to the atmosphere space of the outer chamber, A. At the inner 5 end of the bore, 26, there is mounted rigidly a tubular fitting, 27, whose duct constitutes the continuation of the atmosphere inlet, and which at its upper end affords seat for the atmosphere valve, 28, the latter having a 10 stem, 31, extending down through and protruding from the lower end of said fitting, where it obtains guidance in the latter, the atmosphere access to the chamber being mainly afforded by lateral ports, 29, 29, in 15 the fitting, 27, near the lower end of the fitting, E.

The connection mentioned from the atmosphere valve chamber to the air space of the outer chamber, A, is afforded by a pipe 20 member, 30, having one end connected to the upper end portion of the atmosphere valve chamber, 26, and the other end inserted through the cap, B¹, and the lapping flanges, b¹, of the vacuum chamber, and a¹ of the cap, 25 A¹, of the outer chamber. The connection at 25 this point is not necessarily air-tight, but only sufficiently snug to prevent accidental displacement of the pipe, 30.

Within the vacuum chamber there is provided a float, 40, having a stem, 41, arranged 30 for operating the atmosphere valve for opening and closing at predetermined high and low levels of the liquid content of the chamber. In detail, the construction for connecting the float stem with the atmosphere valve and for guiding the float, consists in forming the lower end of the atmosphere valve stem, which is bent transversely at its lower end, with an eye, 32, in which the slender stem, 40 41, of the float moves freely, the float stem being bent to form a stop shoulder, 41^a, near its lower end attachment to the float, and a second shoulder, 41^b, at a distance above the first mentioned shoulder equal to the predetermined range of movement of the float 45 between high and low levels, said stem being bent in hook form at its upper end above the last mentioned shoulder, as seen at 41^c, to provide a transversely extending terminal, 41^d, at a sufficient distance above the shoulder, 41^b, to permit the co-operation of said stem with the fittings, 27, and 25, rigid with the fitting, E, and which are spaced apart, as seen at 44, a distance sufficient to admit the 50 transverse terminal, 41^d, of the float stem and allow it to slide easily between said two fittings. The transversely bent end of the atmosphere valve stem it will be understood is dimensioned for putting the eye, 32, in 55 alignment with the space, 44, between said two fittings.

From the foregoing description it will be understood that the float stem, 41, may be engaged with the eye, 32, so as to place the shoulder, 41^b, above said eye, and the

transverse upper end terminal, 41^d, engaged between the two fittings, 25 and 27, so that the float lifted by the rise of level of the liquid content of the chamber, may be guided in its rising movement by the engagement of a portion of its stem between the two shoulders in the eye, 32, and the engagement of the upper end hook between the two fittings, 25, and 27; and that at the limit of the range of movement for which opportunity is thus afforded, the lower shoulder, 41^a, will encounter the transverse terminal of the atmosphere valve stem at the eye, and open the valve. It has been demonstrated that the suction hold on the atmosphere valve under ordinary running conditions of the engine served by this apparatus, will operate to delay the opening of the valve until the float becomes submerged to an extent for developing its buoyant value to a degree which will open the valve abruptly and fully, with the effect for which a snap action has been commonly provided; and accordingly, snap action is dispensed with in the present structure.

The operation of the structure above described may be understood from the description of the structure, but may be further described as follows: Starting with the apparatus empty, and with the fuel supply pipe connected with the main tank and the suction pipe connected with the intake manifold of the engine, the float, 40, will hold the atmosphere valve securely seated, and the operation of the engine, developing vacuum in the vacuum chamber, will cause the fuel to be lifted from the main tank and discharge in the vacuum chamber, lifting the float until the lower shoulder, 41^a, of the float stem, encounters the eye, 32, of the atmosphere valve stem, opening the atmosphere valve and admitting atmospheric pressure from the outer chamber, B, which, as mentioned, is at all times under atmospheric pressure by reason of the atmosphere vent 33. The access of atmosphere to the vacuum chamber afforded by the ports, 29, 29, is designed to be so greatly in excess of the access of the suction through the suction passage, 20, that notwithstanding said suction passage remains open when the atmosphere valve is open, the degree of vacuum in the vacuum chamber will be reduced by the opening of the atmosphere valve so as to permit the discharge of the liquid content of the vacuum chamber into the reserve chamber without any embarrassing delay, and upon the lowering of the level of the liquid in the vacuum chamber to predetermined degree, bringing the upper shoulder, 41^b, of the float stem into engagement with the eye, 32, at the end of the atmosphere valve stem, the weight of the float closes the atmosphere valve, and the continuous access of suction restores the

condition of vacuum in the vacuum chamber, causing the cycle of operation to be repeated.

An advantage over previous constructions of this general character which is obtained by the construction described, is obtained by virtue of the provision for admitting atmosphere to the vacuum chamber by way of the outer fuel reserve chamber, instead of directly from the outer atmosphere, as in all previous constructions with which I am familiar. The atmosphere being thus taken from the outer chamber, comes to the vacuum chamber charged more or less with vapor of fuel which is liable to be developed in the outer chamber by reason of the entire apparatus being exposed to engine heat due to mounting in the customary position shown under the hood in front of the dash; and it thus results that in the filling phase when engine suction is operating to produce vacuum in the vacuum chamber, the fluid drawn to the intake manifold is more uniformly charged with fuel vapor than is the case when the atmosphere admitted to the vacuum chamber in the emptying phase is derived from the outer air, and thereby is not charged with fuel vapor.

I claim:

1. A vacuum tank having a vacuum chamber and reserve chamber into which the vacuum chamber discharges, and; having a cover closing the vacuum chamber and the reserve chamber at the top, said cover having an exteriorly projecting member bored for a suction port, and counterbored from the outer end for pipe connection to the suction source, said member being bored from the under side of the cover laterally of the suction port to form an atmosphere inlet valve chamber, and a tubular fitting secured in said member forming at its upper end a valve seat and protruding down in the vacuum chamber, an atmosphere inlet controlling valve seated at the upper end of said tubular fitting and having its stem extending through said fitting, the member being laterally bored for connection with the valve chamber of the first mentioned bore, the cover having an opening into the annular part of the reserve chamber, and a pipe connecting the lateral bore of the member with said last mentioned opening.

2. An apparatus for lifting fuel for supplying an internal combustion engine comprising a vacuum chamber having a valve-controlled atmosphere connection and having also connection with a source of suction, and a fuel reserve chamber having an atmosphere inlet and arranged to derive fuel supply from the vacuum chamber at intervals between periods during which the vacuum chamber derives fuel supply by suction from the fuel source; a duct opening in the upper part of the fuel reserve cham-

ber at a point therein above the high liquid level of the vacuum chamber and leading therefrom into communication with the vacuum chamber and thereby with the suction source, the suction connection of the vacuum chamber with the source of suction being continuously open; whereby vapor of fuel which may accumulate in the upper part of the reserve chamber, and which in the emptying phase of the vacuum chamber may be drawn from the reserve chamber past the open atmosphere valve into the vacuum chamber, is drawn through the vacuum chamber to the suction source.

3. An apparatus for lifting fuel for supplying an internal combustion engine comprising a vacuum chamber having a valve-controlled atmosphere connection and having also connection with a source of suction, and a fuel reserve chamber having an atmosphere inlet and arranged to derive fuel supply from the vacuum chamber at intervals between periods during which the vacuum chamber derives fuel supply by suction from the fuel source; a duct opening in the fuel reserve chamber at a point therein proximate to the level of the atmosphere inlet to said reserve chamber and leading therefrom into communication with the vacuum chamber at a point above the high liquid level of the latter, the suction connection of the vacuum chamber with a source of suction being continuously open.

In testimony whereof, I have hereunto set my hand at Chicago, Illinois, this 21st day of October, 1929.
